UNITED STATES PATENT OFFICE

2,353,190

SCREW PROPELLER

Albert Rupp, Berlin-Sudende, Germany; vested
in the Alien Property CustodianApplication October 4, 1938, Serial No. 233,270
In Germany October 13, 1937

3 Claims. (Cl. 170—160)

This invention relates to screw propellers, intended especially for aircraft, in which the blades are mounted in the hub so as to be radially movable to give automatic centrifugal adjustment of the blades and in which resilient means is provided resisting the action of centrifugal force to effect the adjustment-movement.

It is an object of the present invention to provide a device which ensures uniform adjustment of all the blades of the propeller.

Four embodiments of the invention are shown by way of example in the drawings, wherein:

Fig. 1 shows an embodiment of the invention in side elevation; and

Fig. 2 is a sectional side elevation through another embodiment.

Figures 3 and 4 are sectional side elevations of other embodiments.

Similar parts in the different figures are designated by the same reference numerals.

Referring to the drawing:

Fig. 1 shows an embodiment in which uniform adjustment movement of the blades is ensured by a device comprising a lever. The blade roots 1 are mounted in the hub 2 in a known manner such that the blades can by centrifugal force be moved lengthwise of the blade axes as well as turned about the blade axes to effect diametral adjustment of the blades with simultaneous pitch-adjustment. The hub 2 has the form of a simple tube which is open at both ends in order to receive the blade roots 1. The hub 2 is provided at the drive side with a flange 2a by which the hub is connected with the engine shaft. The arrangement for producing the pitch adjustment of the blades may consist in known manner of helical grooves 30 which are cut on the inner side of the tubular hub 2, and of pins 31 which are provided on the blade roots 1 and engage in the grooves 30. When the blades move radially they describe at the same time a rotational movement about their axes.

This arrangement for pitch adjustment is, however, not essential and can be absent.

Provided at the ends of the hub 2 are lugs 2b which carry shafts (spindles or the like) 12, about which the single-armed levers 11 can swing, and which extend in a direction transverse the blades, that is, transversely to the longitudinal axes of the blades. The levers 11 are loaded by (or subject to the action of) resilient means, for example a traction spring 9, at their freely projecting ends, and at a central point of levers 11 there are provided rollers 13 which press on the outer surfaces of the flanges 1c of the blade roots. 55

When the blades tend to move outwardly by reason of centrifugal force, the spring 9 tends to act oppositely to such movement.

In order that the movements of the two levers 11 be always of uniform magnitude, they are connected together by a movement-transmitting connection. The connection may be a crank, a double-armed lever or equivalent arrangement. As a result of this connection, the diametral adjustments of the blades are also of equal magnitude when both blades are moved outwardly as a result of centrifugal force.

Fig. 1 shows an embodiment in which a "two-armed" lever 7 (i. e. a lever whose arms are disposed on opposite sides of the lever's pivot) is pivotally supported outboard of the hub 2 on a bracket 8 on the hub. The two-armed lever 7 is connected by links 10 with "single-armed" levers 11 (i. e. levers whose arms are disposed on the same side of the respective pivots) which can pivot freely about a fixed pivot 12 on the hub 2 and bear through the intermediary of rollers 13 on the flanges 1c of the blade roots 1. On movement of the blades lengthwise of the blade-axes the levers 11 are moved. By virtue of the two-armed lever 7 and the links 10 which are connected to the lever 7 at equal distances from that lever's pivot a uniform movement of the blades is obtained. The ends of the levers 11 are connected together by a tension spring 9 and this constitutes means resisting centrifugal adjustment of the blades.

Fig. 2 shows an embodiment in which one of the blade roots 1 is provided with a threaded nut 14 whereas the opposite blade root 1a is provided with a complementary threaded stud or screw 15. The nut and stud have fixed connections with the respective blades. On movement of the blades in the direction of the blade-axes the blade roots 1 and 1a are simultaneously turned about their axes by known means, viz: a key and feather device (not shown but similar to the construction 30, 31 of Fig. 1). In this way, the blades being interconnected by the bolt 15 and nut 14, the turning movements corresponding to longitudinal movements of the blades must be equal. The members 16 constitute parts of resilient means resisting the centrifugal adjustment of the blades, the means being essentially similar to those shown in Fig. 1. The members 16 are, for example, two-armed levers adapted to swing about a fixed pivot 16a on hub 2 and which at their free ends are loaded by a pressure spring 35.

Fig. 3 shows an embodiment in which the blade

roots 1 are loaded by levers 16 and springs 17 in a manner similar to that shown in Fig. 1. Links 18 of equal lengths are coupled to the levers 16 and are connected to a slipper 19 which is guided in a slot or guideway 20 provided in a bracket 23a, which is rigidly connected to the hub 2. On movement of one lever 16 the slipper 19 is moved through the intermediary of the links 18 and pulls or pushes the other lever 16 by an equal amount.

The ends of the levers 16 which engage on the blade feet extend in an annular groove 1b which is formed at the foot of the blade. The ends of the levers 16 are thereby positively connected in both diametral directions of movement of the blades therewith. Thus, if a blade is to be held in the hub by clamping, while the other blade moves outwardly under centrifugal force, the clamped blade is also positively driven outwardly.

Fig. 4 shows an embodiment in which the device to ensure uniform adjustment movement is constituted by directly interengaging toothed segments 21. These segments are, suitably, mounted on the pivots 22 of the levers 16. The gear segments are thus rigidly connected with the levers 16 so that the levers 16 must always describe the same movements. The inner ends of the levers 16 engage in an annular groove 1b of the blade roots 1, so that the blades must always describe the same radial movements. The outer ends of the levers 16 are loaded by a pressure spring 17. The hub 2 has the flange 2a for connection to the engine shaft and 30, 31 designate means which, on radial movement of the blades, cause their rotation about the longitudinal axes of the blades. The means 30, 31 can, however, be absent without limiting the scope of the invention.

It will be manifest that the uniform adjustment of all the blades is ensured by virtue of the fact that the device comprises a member movable in a

5 determinate path and connected to the respective blades in each case by positively acting movement-transmitting elements, that is to say, elements which prevent relative play between the device and the blades.

I claim:

1. A screw propeller, including a hub having a driven side, a plurality of blades mounted in the hub and movable outwardly under centrifugal force to effect diametral adjustment of the propeller, a lever for each blade to resist such outward movement, each lever having a pivot in fixed relation to the hub and an arm projecting beyond the hub in a direction from the driven side of the hub, resilient loading means common to all levers, each lever having a part to exert an inward pressure on a part of a blade at the hub, and movement-transmitting elements connected each at one end to a lever arm beyond the hub and at 10 the opposite end to a common element-equalizing member carried by a fixture projecting from the side of the hub remote from the driving side.

2. A construction as defined in claim 1, wherein the common element-equalizing member acts in 15 blade-compelling movement of one lever arm to compel simultaneous, similar, and equal movements of all other lever arms.

3. A construction as defined in claim 1, wherein in the movement-transmitting elements include 20 a double-armed lever pivoted in fixed relation to the hub and beyond the hub relative to the driven side thereof, and equal-length links connecting the respective ends of the double-armed lever to the respective levers for the blades, the ends of 25 the links connected to the levers for the blades being at equal distances from the pivots of such levers.

ALBERT RUPP.
